(57) **CLAIM**

The ornamental design for a display screen or portion thereof with animated graphical user interface, as shown.

DESCRIPTION

FIG. 1 is a first front view of a display screen or portion thereof with animated graphical user interface, showing a first image of my new design;

FIG. 2 is a second image;

FIG. 3 is a third image;

FIG. 4 is a fourth image;

FIG. 5 is a fifth image;

FIG. 6 is a sixth image; and,

FIG. 7 is a seventh image.

The appearance of the animated graphical user interface transitions sequentially between the images shown in FIGS. 1-7. The process or period in which one image transitions to another forms no part of the claims design.

The broken line showing of a display screen and portions of the graphical user interface are included for the purpose of illustrating portions of the article that form no part of the claimed design.
